UNITED STATES PATENT OFFICE.

ROBERT T. PARISEN, OF PITTSBURGH, PENNSYLVANIA, ASSIGNOR TO LAWSON MANUFACTURING COMPANY, OF PITTSBURGH, PENNSYLVANIA, A CORPORATION OF PENNSYLVANIA.

THERMOSTATIC VALVE.

1,278,001.

Specification of Letters Patent. Patented Sept. 3, 1918.

Application filed March 17, 1916. Serial No. 84,851.

To all whom it may concern:

Be it known that I, ROBERT T. PARISEN, a citizen of the United States, and resident of Pittsburgh, in the county of Allegheny and State of Pennsylvania, have invented 5 certain new and useful Improvements in Thermostatic Valves, of which the following is a specification.

The primary object is to provide a valve mechanism of simple and improved construction for automatically controlling the flow of gas to a water heater, the position of the valve being determined by the temperature of the water being heated. The 15 invention includes a connecting means interposed between the valve and the thermostatic rod and movable therewith, whereby adjustments may be made without moving or in any way disturbing the rod. The arrangement thus provides for the use of a rod of porcelain or other neutral material, and hence the thermostatic action results entirely from the expansion and contraction of the rod-inclosing tube, thus avoiding the 25 necessity of delicate and extremely accurate adjustments between the valve and rod. The invention also includes improved means for rotating the valve for adjusting the mechanism to the temperature at which it is desired to maintain the water.

In the accompanying drawings, Figure 1 is a longitudinal sectional elevation of the improved valve mechanism, and Fig. 2 is a similar view taken in a plane at right angles 35 to Fig. 1. Fig. 3 is a cross-section of the valve body taken on line 3—3 of Fig. 1. Figs. 4 and 5 are elevations of the opposite sides of the cap-closed portion of the valve body.

Referring to the drawings, 2 designates 40 the valve body having at opposite sides the gas inlet 3 and outlet 4, and located between the inlet and outlet is the usual valve seat 5. The outer side of body 2 opposite the seat 45 is formed with the open annular extension 6, threaded internally as shown.

Projecting from the opposite side of the body is the hollow extension 7, threaded at 50 7' for connecting with the wall of a stand boiler or other water container, not shown. Secured to and adapted to project into the boiler from body part 7 is the thermostatic

tube 8 of copper or other suitable metal which may be closed at its outer end by plug 9. Operative within tube 8 is the valve 55 actuating rod 10, which in the preferred adaptation is formed of porcelain or other neutral or substantially neutral material.

The thermostatic tube and rod are arranged concentrically with valve seat 5 and 60 disk valve 11 operative thereon, and the cavity 12 of body extension 7 is adapted to receive and form a guideway for the connecting head 13. Rod 10 extends into cavity 12, and head 13 is recessed at one end to 65 embrace the rod as shown. Pins 14 project from head 13 into the cavity offsets or grooves 12', whereby the head is prevented from rotating without interfering with its longitudinal movement. An adjustable connection is provided between valve 11 and head 13, in the adaptation shown a threaded stem 15 projecting from the inner side of the valve and adjustably entered in threaded cavity 13' of head 13.

The open side of body 2 is adapted to be closed by the cap-like closure 16 having an annular extension 17 threaded externally to adjustably connect with the annular threaded body extension 6. A flat tang 18 projects from the outer side of the valve and is embraced by the wrench-forming lugs 19 at the inner side of cap 16. A coiled spring 20 encircles lugs 19 between the cap and valve for exerting seating pressure on the 85 latter.

The flange-like skirt 21 of cap 16 embraces body extension 6, and at one side is notched at 22 for affording the cap limited movement relatively to the projecting stop 23. 90 The opposite side of flange 21 is recessed at 24 and formed with the projecting pointer 25 which co-operates with graduations 26 on body extension 6 for indicating the temperature at which the valve is set to maintain the water. The valve body may be provided with the usual by-pass 27 around valve 11 and controlled by valve 28 for passing sufficient gas to sustain a pilot-burner when valve 11 is closed. Also, the inlet side 100 of the valve body may be provided with the additional outlet 29, here shown closed by plug 29' for passing a pilot sustaining stream of gas around instead of through the

valve structure, and when this connection is used by-pass 27 is closed.

In operation the desired adjustment indicated by graduations 26 is had by simply 5 rotating cap 18, thereby rotating the valve and shortening or lengthening the threaded connection between the latter and the non-rotatable head 13. But as this connecting device is free to move longitudinally, it may 10 respond to the longitudinal movement of the valve. The cap-closed opening of the body affords ready access to the latter for inserting and removing the operating parts, also for dressing the valve seat.

15. I claim:

1. In combination with a valve body having inlet and outlet ports and a through passage, a thermostatic tube closing one end of said passage, an adjustment cap closing 20 the other end of said passage, a thermostatic rod within said tube, a valve axially aligned with said rod and said cap, an abutment member confined against rotation in line with said rod and a screw connection 25 between said abutment member and said

valve for varying the distance between the free end of said rod and said valve.

2. A structure as specified in claim 1 in combination with means between said valve and said cap for causing the valve to rotate with the cap while allowed free reciprocation with relation thereto.

3. A structure as specified in claim 1 wherein the connection between said valve and said abutment member consists of a 30 screw carried by said valve and threaded into said abutment member.

4. A structure as specified in claim 1 wherein one end of the abutment member is chambered to receive the rod.

5. A structure as specified in claim 4 in which a spring is located between said valve and said cap for causing said valve to yieldingly move toward its seat.

In testimony whereof I affix my signature 45 in presence of two witnesses.

ROBERT T. PARISEN.
